CLAIM

The ornamental design for a portable television receiver as shown and described.

DESCRIPTION

1.1 : Front perspective

1.2 : Back perspective

1.3 : Front

1.4 : Back

1.5 : Left

1.6 : Top

1.7 : Bottom

1.8 : Reference

1.9 : Reference

The claimed design is a portable television receiver equipped with a transparent OLED display; a right view is omitted because it is a mirror image of the left view; the broken lines shown in reproductions **1.1** to **1.7** depict portions of the portable television receiver that form no part of the claimed design; reproductions **1.8** and **1.9** illustrate a state in use wherein the broken lines depict environmental structure and form no part of the claimed design; the diagonal shading lines represent a transparent area while the

(Continued)

grayscale shading represents a light-shielding area of the screen and do not represent its surface ornamentation.
